UNITED STATES PATENT OFFICE.

ROBERT FRANCIS COLBORNE, OF STRATHFIELD, NEAR SYDNEY, NEW SOUTH WALES,
AUSTRALIA.

WINDOW.

1,209,674.

Specification of Letters Patent. Patented Dec. 26, 1916.

Application filed October 20, 1911. Serial No. 655,743.

To all whom it may concern:

Be it known that I, ROBERT FRANCIS COLBORNE, a citizen of the Commonwealth of Australia, residing at Strathfield, near Sydney, in the State of New South Wales, Commonwealth of Australia, engineering draftsman, have invented new and useful Improvements Relating to Windows, of which the following is a specification.

10 By means of this invention, which comprises the peculiar disposition or location of a U shaped counter balance weight, and its attachment to a sash in such a manner that both may be kept apart and yet operated 15 simultaneously, provision is made for the ready adjustment of the window sashes of railway cars or carriages to such a height as would be allowable by the limitations defined by their structural details, so that the 20 raising or lowering of the sashes can be easily and quickly performed by the occupants of the car or carriage with less trouble and inconvenience than heretofore.

The invention is devised as a substitute 25 for the catches, stops, and fastenings at present in use for supporting and securing the sashes in certain positions, but which have been found to be liable to dislocation, and may therefore become a source of danger 30 to railway travelers if the sash should be unexpectedly released from its support by the jolting or jarring motions of the carriage.

Referring to the accompanying drawings, 35 which form part of this specification, Figure 1 is a vertical sectional elevation of a railway car window, showing relative positions of balance weight and sash. Fig. 2 is an inside elevation of the car window, showing 40 the sash raised, with U shaped weight in its relative position, one half having casing and louvered shutters in position, the other half stripped of all covering parts. Fig. 3 is a horizontal sectional plan, as seen on line 45 a—a of Fig. 2. Fig. 4 shows, in plan, a detail of the parts of the U shaped weight, comprising a side guide channel, a suspending attachment, and a fragment of the weight. Fig. 5 is a side elevation of the 50 parts shown in Fig. 4, with fragment of guide channel shown in sectional elevation. Fig. 6 is a plan of an angularly disposed hanging pulley or sheave, forming the guide and support for suspenders. Fig. 7 is a side 55 elevation of Fig. 6. Fig. 8 is a plan of a

sash hanger. Fig. 9 is a vertical sectional elevation on line b—b of Fig. 8. Fig. 10 is a back elevation of Figs. 8 and 9, showing tubular part and securing plate.

The drawings show the invention adapted 60 to the window framing of the American type of passenger car which is in use on the Australian railways, and to which it can be easily and cheaply applied.

The lintel A, the stiles B, and the sliding 65 sash C, are the existing parts to be utilized in carrying the invention into effect.

The sash C, which ordinarily slides in the groove D and has the parting bead E separating it from the louvered sash F sliding 70 in the groove G, *vide* Fig. 1, has attached to each of its upper corners the angle strap H, which is fastened with screws in the side and top plates. The said corners are hollowed out to receive the tubular part H', 75 through which the suspending wire rope or cord I is passed and knotted. In that position the secured end I' is secreted, and cannot be tampered with. Each suspending

cord is laid over a spindled groove sheave J 80 running in its bearing K attached to the foot plate K'. The plates, when secured to the lintel A, provide for each sheave being disposed diagonally in the direction of the angle strap H on the one side, and the pin 85 attachment L of the counter weight M on the other side, with the cord I running through the guide holes K², *vide* Fig. 6. To accommodate the counter weight M, and the

metal guide channels N in which it slides, 90 the upper portion of each parting bead E has to be removed. The space so created is filled with the channeled pieces N which are secured to the stiles B. The horn portions M' of the weight are placed in an inverted 95 position, and if the weight be detached from the suspending cords, these parts would rest upon the channel stop ends N', below which the remaining part of the stop bead E serves as a guide to the sash when in its lowermost 100 position, the side flanges of the metal guide channel N answering a similar purpose for both the sash C in its upper position and the louvered sash F.

The counter weight is made U-shaped to 105 obtain the required amount of metal to serve as a counterpoise to the sash, and to allow of the horn portions forming side protecting coverings to those parts of the sash 110 which would be otherwise exposed when the

sash is fully raised, as in Fig. 2. The transverse portion is so placed that it is only partly exposed below the louvered sash F when it is fully lifted, but it may be wholly covered when said louver is slightly lowered.

When sash C is put in any other position than is shown in Figs. 1 and 2, the counter weight is not exposed to view.

The pin attachment L, to which the cord I is secured for supporting the counter weight M, has its head piece pierced at L'. It is shaped to fit either way into the cross cavity M² formed in the weight. The pin part L², screwed at its extremity, is provided with the clamping nut L³, which can be screwed into position in the opening M³, and tightened against the seating part M⁴.

The obvious advantage of the use of this form of counter balance is, that no danger can accrue to the occupants of the car. Moreover, the sash may be readily placed in any desired position with the minimum amount of force exerted by the occupant, which is not the case with existing railway car sliding sashes, some of which, I am aware, are fitted with recoil springs and compound levers, which are liable to disarrangement.

Having now described my invention, what I claim as new and desire to secure by Letters Patent is:—

1. In a balanced sash window construction for railway cars, in combination, a frame, a window sash slidably mounted within the frame, the parting beads of the vertical

frame stiles adjacent to the said sash being cut short to provide guideways extending downwardly from the lintel of the frame, a substantially U-shaped counter-weight mounted for sliding movement within the frame and having its side horns working within the said guideways and protecting the portions of the side rails of the sash which are situated above the existing portions of the said parting beads, and means for connecting the counter-weight operatively with the said sash for relative counterbalancing movement.

2. In a balanced sash window construction for railway cars, in combination, a frame, a window sash slidably mounted within the frame, a louvered sash mounted similarly in the frame, a substantially U-shaped inverted counter-weight mounted to slide between the said sashes, means for connecting the counter-weight operatively with the said window sash for relative counterbalancing movement, and a stop for the counter-weight positioned so that the latter will have its cross portion partially shielded by the louvered sash, when the latter is in its highest position, and so that it will be completely shielded thereby at all other positions.

In testimony whereof I have signed my name to this specification in the presence of two subscribing witnesses.

ROBERT FRANCIS COLBORNE.
